UNITED STATES PATENT OFFICE.

CARL KURTH, OF MAGDEBURG, GERMANY.

CARTRIDGE.

SPECIFICATION forming part of Letters Patent No. 767,570, dated August 16, 1904.

Application filed February 3, 1903. Serial No. 141,741. (No model.)

To all whom it may concern:

Be it known that I, CARL KURTH, paymaster, a subject of the King of Prussia, German Emperor, residing at 40 Neustäbterstrasse, 5 Magdeburg, Germany, have invented a new and useful Improvement in Cartridges for Firearms, of which the following is a specification.

This invention concerns a cartridge for guns and firearms of all kinds. Its object is to obtain an increased effect of the cartridge and to reduce the recoil, while the quantity of powder used remains the same as in the present cartridges in use. This effect is obtained by 15 the arrangement hereinafter described and as shown, for example, in the drawings of a cartridge for a fowling-piece.

The cartridge of this invention has in close connection to the powder a free space full of 20 air in such a manner that the explosive matter is safely stored and prevented from moving, which would render it useless and cause danger by explosion.

Figure 1 is a longitudinal section of the 25 cartridge; Fig. 2, the ring to be set in.

The letter *a* shows the bottom part of cartridge; *b*, the gunpowder; *c*, the wad, which in the cartridge now used presses tight on the gunpowder; *d*, the shot; *e*, the covering-disk; 30 *f*, the choke. All these parts remain unchanged in the present cartridge.

g is a small cardboard cylinder or case closed at one opening with an easily-combustible gauze-like net *h*.

35 The cartridge-case of my invention is slightly longer than the ordinary cartridge-case on account of the cardboard air-chamber, the other parts of both cartridges being the same.

The order of the parts when constructing 40 a cartridge according to this invention is as follows: bottom part *a*, powder *b*, cardboard cylinder or case *g* with net *h*, wad *c*, shot *d*, disk *e*, and choke *f*.

There is between the plug *c* and the powder *b* a quantity of air, which has the effect 45 of increasing the combustion of the powder. It is easily proved by an experiment with one of the cartridges in use that a considerable large quantity of unburned powder flies out 50 of the barrel with the wad, the explosive power of which is thus lost. This is entirely avoided by the present invention. By inclosing a quantity of air with the powder a complete and rapid combustion of the whole powder is accomplished, and thus a greater effect 55 of force is obtained.

This invention can be used with the same 60 advantage for ball or bullet cartridges. In this case the wad is not necessary.

What I claim as my invention, and desire to secure by Letters Patent, is—

In a cartridge for firearms the combination of the explosive propelling charge, an easily-combustible diaphragm lying on the charge, 65 a ring-like cardboard cylinder and a wad pressing said cylinder on the diaphragm close to the powder, all as described and for the purpose set forth.

In witness whereof I have hereunto set my 70 hand in presence of two witnesses.

CARL KURTH.
